UNITED STATES PATENT OFFICE.

PERLEY R. GLASS, OF QUINCY, MASSACHUSETTS, ASSIGNOR TO THE PEER-LESS MACHINERY COMPANY, OF WEST VIRGINIA.

EYELETING-MACHINE.

SPECIFICATION forming part of Letters Patent No. 673,814, dated May 7, 1901.

Application filed May 14, 1900. Serial No. 16,663. (No model.)

To all whom it may concern:

Be it known that I, PERLEY R. GLASS, of Quincy, county of Norfolk, and State of Massachusetts, have invented an Improvement in 5 Eyeleting-Machines, of which the following description, in connection with the accompanying drawings, is a specification, like letters on the drawings representing like parts.

The present invention relates to an eyeletting-machine, the object of the invention being to obtain a machine in which a number of eyelets may be set at one operation, the machine punching the stock and feeding and setting the eyelets automatically. For this purpose the machine embodying the invention is provided with a gang of punching-tools properly arranged to punch a number of holes at a single operation in such position relative to the material and to each other as may be desired and a coöperating punching member and a gang of setting-tools for setting the eyelets in the previously-punched holes, the machine also being provided with means for separating the punching members, (the gang of 20 punching-tools being considered as one of said members and the coöperating punching device being the other of said members,) in order that the material may be accessible to the setting-tools in the setting operation. The punching-tools may advantageously be arranged to co-operate with the setting-tools in the setting operation and are herein shown as provided with tubular punching projections surrounded by annular clenching-dies and so arranged 25 with relation to the gang of setting-tools that the said annular dies will operate to upset or clinch the eyelets in response to the operation of the setting-tools.

The punching-tools are herein shown as stationary with relation to the machine and projecting downward from a portion of the frame, while the coöperating punching member comprises what may be termed an "anvil" arranged to have a vertical movement toward 40 said punching-tools, so that when the material is held in the machine between the said members the upward vertical movement of said anvil will force the material against the cutting edges of the punches, thus punching out 45 a series of holes. The setting devices are arranged to reciprocate vertically and to move

upward toward the punching-tools after the punching operation is completed, the anvil in the meanwhile being moved vertically downward and also laterally with relation to the 55 line of punching, so as to travel out of the path of the setting devices and permit the same to come in contact with the material which is between them and the punching-tools. 60

When the machine is in its normal condition before being started, the anvil is separated from the punching-tools and the material may be placed upon the surface of said anvil or held against the cutting edges of the punching-tools, as may be more convenient, and when the machine is started the anvil will travel upward to punch the material, which will then be held with the punching-tools in the several openings, while the anvil moves 70 away, the setting devices then moving toward the punching-tools to insert and set the eyelets, the usual eyelet-feeding device being employed to provide the setting devices with eyelets. 75

In order to facilitate the setting operation, it is desirable that the punching-tools should be externally tapered and caused to project beyond the surface of the material after the material is punched in order to guide the eyelets into the openings in the material. To accomplish this, the anvil may be provided with a covering of rawhide, which will properly support the material, but permit the punch to penetrate said covering slightly, so 80 that the material in the punching operation will be forced up along the tubular punching-tools, the ends of which thus project beyond the surface of the material, so as to guide the eyelets into the holes, or if the supporting-surface of the anvil is of impenetrable material it may be provided with annular channels to receive the cutting edges of the punch. 85

Figure 1 is a front elevation, partly in section, of a machine embodying the invention; Fig. 2, a side elevation of the same, partly in section; and Fig. 3, a detail view showing the parts in a different position from Fig. 2. 95

The punching-tools *a*, or "punches," as they will be hereinafter referred to, are shown as provided with annular clenching-shoulders 100

a^2 and are supported in an overhanging projection A^2 , which forms part of the frame A of the machine. There may be any number of the said punches desired, according to the 5 number of eyelets to be set by the machine, there being four of such punches herein shown, although in some cases five or six or any other number may be employed. Each of the said punches is tubular and provided 10 with a cutting edge, and, as herein shown, the punching-tools are screw-threaded in the projection A^2 , which is provided with channels A^3 for the egress of the pieces of the material punched out, and, if desired, the said 15 projection may be provided with a box A^4 to receive the said pieces of material and prevent the same from being scattered about.

In treating of the machine as a whole the 20 said gang of punches may be considered as a single punching member, the punching operation being completely performed by the co-operation with said member of a second punching member b , which consists of an anvil, between which and the punching member first 25 named the material is introduced in the punching operation. As herein shown, the said punching member b , or "anvil," as it will be hereinafter referred to, is supported upon a pair of vertically-movable arms or columns 30 b^2 , each connected by means of a link b^3 with a lever b^4 , pivoted upon a cross member b^5 , supported by the frame A and connected at its opposite end with an eccentric-strap b^6 , carried by an eccentric B^2 on the main shaft 35 B. The rotation of the said shaft, therefore, will produce a reciprocating movement of the said anvil b , so that if the material is placed in position between the same and the punches a a line of holes will be punched 40 therein. In order to complete the operation, it is necessary that an eyelet should be inserted in each hole and clenched therein, and for this purpose the machine is provided with a set of clenching-tools c , each of which has a 45 clenching-shoulder c^2 and depressible pin c^3 , projecting upward to pick up an eyelet from an eyelet-feeding device d . Prior to the setting operation it is necessary that the co-operating punching members should be separated from each other, so that the eyelets 50 may be presented to the material by the eyelet-setting devices and clenched by the co-operation of said setting devices with each other. The reciprocating movement of the 55 member b properly separates the said parts, so that the openings in the material may receive the eyelets. When, however, as herein shown, the punching-tools a are arranged to also co-operate in the setting operation, or, in 60 other words, to constitute setting members as well as punches, it is necessary that the said setting devices should move toward the punches a , thereby occupying the position previously occupied by the anvil b in the 65 punching operation. It is necessary, therefore, that the said anvil b should not only move away from the punches a , but also out

of the path of the setting devices c , and for this purpose the said anvil is herein shown as arranged to have a laterally as well as a longitudinally reciprocating movement in the operation of the machine. As a convenient means for producing such lateral movement the arms b^2 are shown as provided with projections b^7 , each having an antifriction-roll b^8 , adapted to engage the walls of curved or cam shaped guide-grooves A^5 , formed in wings or projections from the frame A , the curvature of such grooves being such as to cause the anvil in its downward movement to travel 80 laterally with relation to the punches a out of the path of the reciprocating setting devices c , which then move toward the said punches, as best shown in Fig. 3.

As herein shown, the lateral movement of 85 the anvil b is forward with relation to the machine, the anvil when down thus being in a convenient position to receive the material, it being practicable to provide said anvil with suitable gages, so that the material may be 90 correctly placed and held in position during the upward movement of the anvil.

As herein shown, the anvil is provided with a supporting portion b^9 for the punches, this supporting portion being advantageously 95 made of rawhide, which affords a firm support for the material to be punched without resisting the downward movement of the punch exceeding that required to punch the material, which material is thus not only penetrated by the punch, but forced upward along the same, so that the punch projects below the lower surface.

As indicated, the punches are tapered externally, and in the operation of the machine 105 as the anvil recedes the material is left upon the punches with the punches protruding, the setting devices then operating and presenting the eyelets to the punches, the tapered outer surfaces of which guide the eyelets into the 110 holes. The eyelets may be fed to the setting devices in any suitable way, the machine being herein shown as provided with a reciprocating chute which constitutes the eyelet-feeding device d , the said chute having a plurality of raceways d^2 , each having the ordinary spring-controlling device at the end, so that the eyelets will not slip out of the said chute until engaged by the fingers c^8 of the 115 setting devices c . The said eyelet-feeding device is arranged to move forward into the path of the setting devices c and to remain in its forward position long enough to have an eyelet engaged by each of the fingers c^8 , then receding and leaving the eyelets upon 120 the said fingers, substantially as in eyeleting-machines heretofore used.

To produce the reciprocating movement of the eyelet-feeding device d , the said feeding device is shown as mounted on guides d^3 , secured to the frame of the machine and connected by a rod d^4 with an eccentric B^3 upon the main shaft B. The several raceways d^2 are adapted to receive eyelets from a hopper 130

⁵ ^{d⁵}, having an opening for each raceway, the openings being so shaped as to cause the eyelets to pass out in the proper position. The setting devices ^c are shown as mounted on a carrier ^{c⁴}, adapted to travel vertically in a suitable guide-support formed in the frame of the machine between the columns ^{b²}, which support the anvil, the said carrier being connected by a link ^{c⁵} with a lever ^{c⁶}, which may conveniently be pivoted upon the cross-member ^{b⁵}, which carries the levers ^{b⁴}, hereinbefore described, the said lever ^{c⁶} being connected with an eccentric-strap ^{c⁷} on an eccentric ^{B⁴} on the main shaft B.

¹⁵ As shown in Figs. 2 and 3, the eccentrics ^{B²} and ^{B⁴} are arranged substantially opposite to each other, so that the downward and lateral movement of the anvil takes place during the upward movement of the setting devices, the ²⁰ two parts being so arranged as to just clear each other without loss of time in the operation.

The feed-chute is arranged to travel forward just after the anvil travels downward, ²⁵ so as to come into the path of the setting devices at the proper time and present the eyelets thereto.

By the use of the gang of tools, each of which combines a punch and setting device, the necessity for all feed mechanism for the material is obviated and the whole operation is performed with only three movable members—namely, the anvil, the reciprocating setting-device carrier, and the eyelet-feed chute.

³⁵ Furthermore, the movements may be imparted to the several parts from a single shaft without any substantial intermediate mechanism, so that it is practicable to make a machine not only very rapid in operation, but also ⁴⁰ of extreme simplicity. It is not, however, intended to limit the invention to the specific construction herein shown and described, although such construction is believed to be the most practical embodiment of the invention, ⁴⁵ since modifications may be made without departing from the invention.

I claim—

1. An eyeleting-machine having a gang of punches mounted on a stationary projection; ⁵⁰ a guide-support below said projection; a set-

ting-device carrier having a gang of setting devices and being vertically movable in said support; a punching-anvil mounted on columns one at each side of said guide-support; wings provided with guide-grooves adapted ⁵⁵ to receive projections from said columns; a lever pivotally connected with said setting-device carrier; a lever pivotally connected with said columns; a reciprocating eyelet-feed chute; a rod for reciprocating said chute; and ⁶⁰ a single operating-shaft for said levers and said rod.

2. In an eyeleting-machine, the combination with a gang of combined punches and setting devices; of a reciprocating anvil co- ⁶⁵ operating with all of said punches at one operation; a lever connected with the said anvil to produce a reciprocating movement thereof; a guide for said anvil to move the same laterally during such reciprocating movement; ⁷⁰ a gang of setting devices to coöperate with the said combined punches and setting devices; a lever to operate said gang of setting devices; a reciprocating feeding device having a plurality of chutes to supply all of the said ⁷⁵ setting devices with eyelets; and a single operating-shaft adapted to coöperate respectively with the levers aforesaid and the said reciprocating feeding device, as set forth.

3. In an eyeleting-machine, the combination with a gang of tubular punches, each provided with an annular clenching-surface; of an anvil to coöperate with all of said punches in one punching operation; means for producing a lateral and vertical movement ⁸⁵ of said anvil; a gang of setting devices adapted to be moved toward the said punches after the punching operation, the lateral movement of the anvil moving the same out of the path of said setting devices; and means for sup- ⁹⁰ plying each setting device with an eyelet, as set forth.

In testimony whereof I have signed my name to this specification in the presence of two subscribing witnesses.
